(57) **CLAIM**

The ornamental design for a liquid jet nozzle for cutting as shown and described.

DESCRIPTION

FIG. 1 is a front view of a liquid jet nozzle for cutting of an embodiment of the present invention, the rear view being identical thereto;

FIG. 2 is a top plan view thereof;

FIG. 3 is a bottom plan view thereof;

FIG. 4 is a right side view thereof, the opposite side view being identical thereto;

FIG. 5 is an enlarged view showing a portion of FIG. 1 defined by line 5-5;

FIG. 6 is an enlarged bottom plan view thereof;

FIG. 7 is an enlarged view showing a portion of FIG. 4 defined by line 7-7; and,

FIG. 8 is an enlarged perspective view showing the tip thereof.

The features shown in evenly-dashed broken lines depict environmental subject matter only and form no part of the claimed design. The dot-dash broken lines in the drawings represent the bounds of the claimed subject matter, the dot-dash lines, themselves forming no part thereof.
